Primary Examiner — Cathy A MacCormac*(74) Attorney, Agent, or Firm* — Rathe Lindenbaum LLP(57) **CLAIM**

We claim the ornamental design for a pet chew toy, as shown and described.

DESCRIPTION

FIG. 1 is a top perspective view of a pet chew toy illustrating our design;

FIG. 2 is a top view thereof;

FIG. 3 is a bottom view thereof;

FIG. 4 is a left side view thereof;

FIG. 5 is a right side view thereof;

FIG. 6 is a front view thereof; and,

FIG. 7 is a rear view thereof.

The broken lines in the drawings are for illustrative purposes only and form no part of the claimed design. The short dash-long dash lines are boundary lines which do not form part of the claimed design. The stippling represents a contrast in materials.
